UNITED STATES PATENT OFFICE

149,727

DESIGN FOR A DISPLAY STAND

Nicholas Anitole, Norwood, R. I., assignor to Ostby & Barton Company, Providence, R. I., a corporation of Rhode Island

Application November 15, 1947, Serial No. 142,560

Term of patent 14 years

(Cl. D80—9)

To all whom it may concern:

Be it known that I, Nicholas Anitole, a citizen of the United States of America, residing at Norwood, county of Kent, and State of Rhode Island, have invented a new, original, and ornamental Design for Display Stands, of which the following is a specification, reference being had to the accompanying drawing, forming part thereof, in which

Fig. 1 is a side elevational view of a display stand, showing my new design; Fig. 2 is a front elevational view of the display stand; Fig. 3 is a top plan view, in a reduced scale, of the same; and Fig. 4 is a rear elevational view of the display stand, also in a reduced scale.

I claim:

The ornamental design for a display stand, substantially as shown.

NICHOLAS ANITOLE.
